FRANKLIN AINSWORTH, OF NEW YORK, N. Y.

STOP-MOTION.

1,082,388.

Specification of Letters Patent.

Patented Dec. 23, 1913.

Application filed November 8, 1912. Serial No. 730,177.

To all whom it may concern:

Be it known that I, FRANKLIN AINSWORTH, a citizen of the United States, and a resident of the city of New York, borough of Brooklyn, in the county of Kings and State of New York, have invented a new and Improved Stop-Motion, of which the following is a full, clear, and exact description.

The object of the invention is to provide a new and improved stop motion more especially designed for use on sewing machines and the like, and arranged to automatically stop the machine whenever the needle thread or the shuttle thread breaks or runs out, and to permit of conveniently applying the stop motion to sewing machines as now constructed.

For the purpose mentioned, use is made of a pivoted arm engaged by the sewing or needle thread of the sewing machine, an oscillating arm actuated from a movable part of the sewing machine, and a stopping mechanism for the machine, the said oscillating arm oscillating in close proximity to and free of the said pivoted arm until the latter is released by the sewing thread and passes into the path of the said oscillating arm to actuate the said stopping mechanism with a view to stop the machine.

30 A practical embodiment of the invention is represented in the accompanying drawings forming a part of this specification, in which similar characters of reference indicate corresponding parts in all the views.

35 Figure 1 is an elevation of the rear side of the sewing machine provided with a stop motion; Fig. 2 is a face view of the head of the sewing machine provided with the stop motion; Fig. 3 is a cross section of the same 40 on the line 3—3 of Fig. 1; Fig. 4 is a similar view of the same and showing the parts in a different position; and Fig. 5 is a sectional plan view of the same on the line 5—5 of Fig. 3.

45 The sewing machine A on which the stop motion is shown applied may be of any approved construction and having the usual reciprocating needle A' through which passes the sewing thread B from the take-up 50 A² and through which take-up passes the sewing thread by way of the tension devices A³, A⁴ and a guide pin A⁵, all arranged on the head A⁶ of the sewing machine. The thread B during its passage from the guide 55 A⁵ to the tension device A³ passes around a

pin C⁸ held on the upper end of an upright swing arm C⁵ pivoted at its lower end at C⁶ to a bracket D³ attached to the head A⁶ of the sewing machine. A spring C⁷ presses the swing arm C⁵ in a rearward direction. 60 The swing arm C⁵ is provided with a shoulder C⁹ normally out of engagement but adapted to be engaged by the free end E² of an oscillating arm E³ secured on a shaft F⁴ journaled in a bracket G⁶ attached to the 65 sewing machine frame at the rear thereof. On the shaft F⁴ is mounted to turn loosely a sleeve F⁵ provided with an arm F⁶ connected by an eccentric rod F⁷ with an eccentric F⁸ held on the shaft A⁷ of the sewing 70 machine so that a constant rocking motion is given to the sleeve F⁵ as long as the sewing machine is running. One end of the sleeve F⁵ abuts against a collar G⁷ secured on the shaft F⁴, and the other end of the 75 sleeve is engaged by a friction washer W pressed on by the hub W' of an arm W² by the action of a spring W³ coiled on the shaft F⁴ and bearing against the hub W' at one end and bearing against a collar F⁹ on the 80 shaft F⁴, as plainly indicated in Fig. 5.

The hub W' is provided with a notch W⁴ into which extends a pin W⁵ projecting from the shaft F⁴ so that the hub W' turns with the shaft F⁴ and at the same time is free to 85 slide in the direction of the axis of the shaft F⁴. The spring W³ presses the hub W' with sufficient force against the friction washer W so that the latter turns with the hub W', and as the washer W rocks with the 90 sleeve F⁵ a swinging motion is given to the arm W². On the arm W² is secured a pin W⁶ extending between two pins 1 and 2 projecting from the sleeve F⁵, the pin W⁶ being normally in contact with the pin 1. 95 The arm W² is provided with a shoulder W⁷ normally out of engagement with the lower end of an arm X fulcrumed at X' on a lever X² fulcrumed at X³ on a bracket G⁸. The arm X is pressed forwardly by a spring X⁴ and the forward swinging movement of the arm X is limited by a stop pin X⁵ on the lever X². The upper end of the arm X is provided with a handle X⁶ under the control of the operator for stopping the machine by hand whenever it is desired to do so. The lower end of the lever X² is connected by a link X⁷ with a suitable mechanism for stopping the sewing machine. Now when the parts are in the position 110

shown in Fig. 2 the arm C⁵ is held out of engagement with the oscillating arm E³ by the action of the thread B, but in case the thread breaks the arm C⁵ is caused to swing rearwardly by the action of the spring C⁷ so that the shoulder C⁹ is engaged by the free end of the arm E³, and the latter is now held against rotation in a downward direction whereby the shaft F⁴ is held against 5 rocking movement. The sleeve F⁵ on turning causes its pin 2 to move in contact with the pin W⁶, and on the next upward movement of the arm F⁶ the arm X can engage the shoulder W⁷ (see Fig. 4), and on the 10 following down stroke of the arm F⁶ an upward swinging movement is given to the arm W² to cause a swinging of the lever X² with a view to move the clutch mechanism into action to stop the sewing machine. 15

20 The pins 1 and 2 are spaced apart a distance corresponding approximately to the throw of the eccentric F⁸ and the diameter of the pin W⁶ is about one-half the said distance. Normally the pin 1 is in contact 25 with the pin W⁶ as shown in Fig. 3, and when the shaft F⁴ is stopped, as previously explained, the arm W² is held against upward movement. The next downward movement of the eccentric F⁸ and arm F⁶ 30 causes the pin 2 to move upward into contact with the pin W⁶ and on the next upward movement of the eccentric F⁸ and the arm F⁶ the arm W² is caused to swing downward owing to the friction washer W between the 35 sleeve F⁵ and the hub W'. The shoulder W⁷ of the arm W² now passes under the arm X and on the next downward movement of the eccentric F⁸ and the arm F⁶ the pin 2 swings the arm W² upward to actuate the 40 lever X² and the clutch mechanism as previously explained.

It is understood that the same action as above described takes place in case the shuttle thread breaks or runs out instead of the 45 sewing thread B. It is also understood that the eccentric F⁸ is set on the shaft A⁷ in such relation to the take-up A² that whenever the latter is in uppermost position the 50 free end of the oscillating arm E³ is opposite the notch C⁹ and hence when the thread

breaks the machine is stopped at the very last stitch.

Having thus described my invention, I claim as new and desire to secure by Letters Patent:

1. A stop motion for sewing machines, comprising a spring-pressed pivoted arm mounted to swing transversely on the head of the sewing machine, the free end of the said arm being engaged by the sewing thread and the said free end having a shoulder, an oscillating arm normally out of engagement with the shoulder of the said pivoted arm until the latter is released by the sewing thread, a shaft carrying the said oscillating arm, a sleeve loose on the said shaft, means for rocking the said sleeve from a movable part of the sewing machine, and a friction device connected with a stop mechanism for the sewing machine and connected with the said sleeve to cause the latter to normally rock the said shaft and to actuate the stop mechanism on stopping the oscillation of the shaft on the said oscillating arm engaging the said shoulder. 75

2. A stop motion for sewing machines and the like, comprising a spring-pressed swing arm mounted to swing and engaged by the sewing thread, an oscillating arm normally out of engagement with the said swing arm until the latter is released by the thread, a shaft carrying the said oscillating arm, a sleeve loose on the said shaft and provided with two spaced pins, means for rocking the sleeve from a movable part of the machine, an arm having a pin extending between the said spaced pins and having its hub mounted to turn with and to slide on the said shaft, a friction disk between the said sleeve and hub, a spring pressing the said hub, and a 85 stopping mechanism for the machine and controlled by the said last-mentioned arm. 90

In testimony whereof I have signed my name to this specification in the presence of two subscribing witnesses.

FRANKLIN AINSWORTH.
